Primary Examiner — Freda S Nunn(74) *Attorney, Agent, or Firm* — Banner & Witcoff, Ltd.(57) **CLAIM**

The ornamental design for an electronic computer, as shown and described.

DESCRIPTION

FIG. 1 is a front perspective view of an electronic computer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top plan view thereof showing the computer in a closed position;

FIG. 9 is a perspective view thereof wherein the tablet is shown separated;

FIG. 10 is a top plan view thereof wherein the keyboard is shown separately;

FIG. 11 is a front view thereof wherein the tablet is shown separately;

FIG. 12 is a bottom plan view thereof; and,

FIG. 13 is a rear perspective view thereof.
